UNITED STATES PATENT OFFICE.

NORMAN W. CUMMINS, OF BRIDGEPORT, CONNECTICUT, ASSIGNOR TO THE BASSICK COMPANY, OF BRIDGEPORT, CONNECTICUT, A CORPORATION OF CONNECTICUT.

HOOD-CATCH.

1,398,319.

Specification of Letters Patent. Patented Nov. 29, 1921.

Application filed May 11, 1921. Serial No. 468,765.

To all whom it may concern:

Be it known that I, NORMAN W. CUMMINS, a citizen of the United States, residing at the city of Bridgeport, in the county 5 of Fairfield and State of Connecticut, have invented certain new and useful Improvements in Hood-Catches; and I do declare the following to be a full, clear, and exact description of the invention, such as will enable others skilled in the art to which it ap- 10 pertains to make and use the same.

This invention relates to certain new and useful improvements in a hood catch, and it has for an object to provide a combined hood- 15 engaging hook and buffer the latter being moved to an operative position, by and during movement of the hood catch or hook to its operative position, to prevent rattling of the hood.

20 The invention further consists in making in one permanently assembled structure the hood catch and buffer and, where used, the base plate for mounting the buffer and catch.

25 The invention further resides in the provision of a pivotally mounted buffer frame carrying a buffer element on one arm and having a hood catch swiveled on the opposite end or arm whereby when the catch is

30 engaged, the frame will be rocked to impinge the buffer element against the hood.

Further, the invention consists and resides in the features of construction and the arrangements and combinations of parts 35 hereinafter described and claimed, reference being made to the accompanying drawings wherein:

Figure 1 is a rear elevation of the improved hood catch in its operative position, 40 a portion of the hood being shown in side elevation.

Fig. 2 is a vertical section therethrough showing more clearly the detailed construction;

45 Fig. 3 is a horizontal section on line 3—3 of Fig. 1 showing more particularly the base or bed-plate;

Fig. 4 is a similar section on line 4—4 of Fig. 3, depicting the engagement of the 50 hood by the hook;

Fig. 5 is a side elevation of the improved hood catch in its inoperative position;

Fig. 6 is a fragmentary view showing a modified form of base plate;

Fig. 7 is a transverse section thereof taken 55 on line 7—7 of Fig. 6;

Fig. 8 is a further modified construction in which the base-plate is omitted, and

Fig. 9 is a horizontal sectional view on 60 line 9—9 of Fig. 8.

Referring more in detail to the accompanying drawings the base or bed-plate 1 is riveted or otherwise secured, as by screws, directly upon the sill-plate 2 of an automobile, said base-plate having a pair of ears 3 struck up to form a central opening through which a pair of ears 4 extend, the same depending from the buffer frame 5 and pivoted to the ears 3 by a pin 6 which can be riveted at both ends, or at one end only and 70 the opposite end equipped with a cotter pin 7.

The buffer-carrying frame has one end of arm 8 turned upwardly at right angles and to the inner face of this support 8 is secured 75 a buffer 9 of rubber, felt, or other suitable material, the same being designed to impinge against the hood 10 adjacent its lower edge to prevent the same from rattling when the hook 11 is engaged in its striker 80 or keeper 12.

The catch element is herein depicted as comprising a shell or cylinder 13 and a telescopic supporting rod 14 which is normally held in its telescoped relation by a coil 85 spring 15 arranged within the shell 13 and compressed between the lower end thereof and the inner end of the stem or rod 14 whereby when the hook 11, carried on the upper end of the outer section 13, is lifted 90 upwardly, as by the grips 16, to engage the striker 12 said spring will be compressed and exert the desired pressure to retain the hook within its striker.

The lower or outer end of the rod 14 is 95 threaded through an opening 17 in the opposite end or arm of the rockable buffer carrying frame 5 and has its extremity formed with a swivel head 18 for engagement in a concave seat 19 provided in the 100 under face of the rockable frame.

It will thus be seen that any movement tending to engage the hook 11 with its striker will also cause a lifting pressure on

the adjacent end of the rockable frame and thereby effect a rocking of the latter to swing the buffer 9 against the hood. When it is desired to gain access beneath the hood, the hook 11 is first disengaged and permitted to drop backwardly whereupon the frame 5 will be rocked outwardly to disengage the buffer from the hood, as shown in Fig. 5.

- 10 The bed or base plate 1 may extend substantially parallel to the hood as in Fig. 1, or it may extend transversely thereof as indicated at 20 in Fig. 6 wherein the base plate is likewise provided with a pair of ears 21 to which are pivotally connected the frame ears 4 by means of the pivot pin 6.

As a further modification of the present invention the base plate may be entirely eliminated and the sill 22 provided with an opening 23 which is cut away at the front end, indicated at 24, so as to permit a rocking movement of the frame 5 whose ears 25 are extended through the opening and have the pivot pin 26 passed through the protruding ends of said lengthened ears to not only provide a rockable mounting for the buffer frame but also to serve as a retainer to prevent the dislodgment of the frame by engaging the under face of the sill. This form of the invention is preferred by some automobile manufacturers who merely provide the opening 23 through the sill, drop the frame ears 25 therethrough, and pass the pin 26 through the ears to prevent withdrawal thereof. This buffer frame is, therefore, rockingly secured to the sill without the use of the base plate and when the lift 16 is pulled up the buffer frame will swing forwardly to engage the hood as in the preceding constructions. When the hood catch is released the buffer frame may be allowed merely to drop down through the opening 23 until it is arrested by contact of the seat arm 19 with the sill. The hood catch will swing 45 far enough back to be entirely out of the way owing to its swivel connection.

The improved hood catch structure, in which the catch element and the buffer plate are permanently assembled, is very 50 advantageous and practical and the buffer-carrying frame has a permanent rocking connection with the sill while the catch may be said to have a permanent swivel connection with the frame, so that the pulling up 55 of the catch will swing the frame and cause the buffer to bind against the hood. The advantage of having the cotter pin 7 is that all parts of the device can be removed from

the automobile when the latter is to be repainted or varnished when this is considered necessary.

What is claimed is:

1. A hood catch comprising a buffer frame struck up from sheet metal and having medially disposed ears, a pivot pin 65 passed through the ears to provide a rockable mounting for the frame, a buffer element carried on one end of the frame for impingement against the hood of a motor vehicle, and a hood engaging hook member 70 swiveled to the opposite end of the buffer frame for effecting a rocking of the latter to impinge the buffer element against the hood when the hook member is engaged with the hood.

2. A hood catch comprising a buffer frame struck up from sheet metal and having medially disposed ears, a pivot pin passed through the ears to provide a rockable mounting for the frame, a buffer element 80 carried on one end of the frame for impingement against the hood of a motor vehicle, the opposite end of the buffer frame being perforated and formed in its under face with a concave seat, and a hood-engaging hook member passed through the perforated end and loosely engaged in concave seat of the frame.

3. A hood catch comprising a buffer frame struck up from sheet metal and having medially disposed ears, a pivot pin passed through the ears to provide a rockable mounting for the frame, a buffer element carried on one end of the frame for impingement against the hood of a motor vehicle, 90 the opposite end of the buffer frame being perforated and formed in its under face with a concave seat, an extensible hook member 95 for engaging the hood having resiliently connected sections one of which is formed 100 with a head to engage in the frame seat in a swiveled manner.

4. In combination with an automobile engine support and hood, a buffer frame having an ear depending through an opening 105 in the support, a combined pivot and anchoring pin passed through the lower end of the ear to freely engage the underface of the support, said ear loosely fitting the opening to rock and vertically slide therein, a buffer 110 element carried by the frame, and a hook member pivotally connected to the frame.

In testimony whereof I affix my signature hereto.

NORMAN W. CUMMINS.
